FLOODED TYPE REFRIGERATION UNIT

Filed March 5, 1929

UNITED STATES PATENT OFFICE

RAYMOND C. HAIMBAUGH AND ANTHONY F. HOESL, OF CHICAGO, ILLINOIS, ASSIGNEES
TO PEERLESS ICE MACHINE COMPANY, OF CHICAGO, ILLINOIS

FLOODED TYPE REFRIGERATION UNIT

Application filed March 5, 1929. Serial No. 344,418.

Our invention relates to improvements in flooded type refrigeration units, and it consists in the combinations, constructions, and arrangements herein described and claimed.

5 An object of our invention is to provide a flooded type refrigeration unit in which novel straining means is provided for screening out foreign matter from the refrigerant fluid.

10 A further object is to provide a device of the type described in which the various mechanical parts are so arranged that a minimum amount of displacement is attained in a refrigerator.

15 A further object is to provide a device of the type which will permit the employment of the refrigeration unit in refrigerators of comparatively small dimensions.

20 Other objects and advantages will appear in the following specification, and the novel features of the invention will be particularly pointed out in the appended claims.

Our invention is illustrated in the accompanying drawing forming part of this application, in which

25 Figure 1 is a diagrammatical view of an installation employing our invention,

Figure 2 is a front elevation of the refrigeration unit,

30 Figure 3 is a side elevation of the device shown in Figure 2, and

Figure 4 is a sectional view taken substantially along the line 4-4 of Figure 2.

In carrying out our invention, we make use of a refrigeration unit 1 comprising a hollow body portion 2 having inclined side portions 3, hollow laterally extending portions 4, and a hollow vertical communicating portion 4'. The extending portions 4 may be arranged for supporting pans 5. The pans 40 may serve as containers for water to be frozen. The body portion 2 may be cast in a single piece of metal.

In referring to Figure 3, it will be seen that the upper part of the body portion 2 is shorter than the lower portion whereby a space 6 is provided. The body portion is provided with an opening 7, see Figure 4. A cover plate 8 is disposed adjacent the opening 7 and is secured to the body portion 2 by means of screws or bolts 9. The cover plate

8 is provided with bosses 9' and 10. An outlet shut off valve 11 is disposed upon the boss 9' and secured to the cover plate 8 by means of screws or bolts 12. The boss 10 is recessed at 11' to receive one end of a cylindrical member 12' having a cone shaped screen 13 disposed therein. An inlet shut off valve 14 is disposed upon the outer end of the cylindrical member 12' and is firmly secured to the cover plate 8 by means of bolts or screws 15.

The cover plate 8 is provided with an integral bracket 15' arranged to project through the opening 7 and to the interior of the body portion 2. The cover plate 8 is provided with a pair of lugs 16 between which a float lever-arm 17 is pivotally mounted. The lever-arm 17 is provided with an extending portion 18, the outer end of which terminates relatively near the bracket 15'. The bracket 15' is provided with an adjusting screw 19 which may be adjusted for limiting the movement of the extending portion 18. A float 20 is secured to the outer end of the lever-arm 17 as shown in Figures 3 and 4.

An opening 21 places the inlet shut off valve 11 in communication with the interior of the hollow body portion 2, and an opening 22 places the outlet shut off valve in communication with the interior of the body portion. A valve 23 is operatively connected 75 with the lever-arm 17 and is arranged for closing the opening 22. A spring 24 is secured to the adjusting screw 19 and the lever-arm 17 for partly assisting the raising of the lever-arm. The lever-arm is provided with 80 a series of notches 25 within which one end of the spring 24 may be secured for varying the lifting influence of the spring.

In Figure 1 we have shown an installation 90 showing our refrigeration unit. The refrigeration unit 1 is disposed within the refrigerator 26. A motor 27 is provided for driving a compressor 28. The compressor 28 is provided with a discharge pipe 29 associated with a condenser 30 connected with a receiver 31. A liquid line 32 leads from the condenser 31 to the inlet shut off valve 14. The liquid line 32 may be secured to a threaded portion 33 associated with the valve 14. A suction line 34 connects the outlet shut off 100

valve 11 with the compressor 28. The suction line 34 is connected with the valve 11 at 35.

From the foregoing description of the various parts of the device, the operations thereof may be readily understood.

When the motor 27 is started, the compressor 28 is actuated at which time the refrigerant liquid vapor, contained in the upper 10 section of the hollow body portion 2, is drawn through the suction line 34 to the compressor 28 and therein compressed to a higher pressure and passed from the compressor through the discharge line 29 to the condenser 30. 15 The vapor is condensed to a liquid state in the condenser. The refrigerant liquid passes from the condenser 30 to the receiver 31 from which the liquid is passed through the liquid line 32 and the inlet shut off valve 14. 20 The liquid passing through the inlet shut off valve passes through the screen 13, the opening 22, and into the interior of the hollow body portion 2. When the liquid within the hollow body portion reaches a predetermined 25 height, as indicated at X in Figure 3, the float 20 will be raised a sufficient distance for moving the valve 23 into its seat and thereby closing the opening 22.

It will be seen that the construction of the 30 body portion 2 is such that the valves 11 and 14 are disposed within the spaces 6 whereby the refrigeration unit is compact in construction and is so designed that the unit will occupy a minimum of space within a refrigerator and the like.

It will further be seen that the body portion 2 is so designed that cooling surfaces inclose three sides of the pans 5. The design of the hollow body portions 2 and 4 is such 40 that a maximum cooling surface is provided.

We claim:

1. A refrigeration unit comprising a hollow one-piece casting having a short portion provided with an opening, a cover for closing 45 the opening, an outlet shut-off valve secured to the cover and communicating with the interior of said casting, an inlet shut-off valve secured to the cover and communicating with the interior of the casting, a straining element disposed between the inlet shut-off valve and the cover for straining a refrigerant fluid, and means for securing the inlet shut-off valve to the cover and for holding the straining element between said valve and the 50 cover.

2. A refrigeration unit comprising a hollow one-piece casting having a short portion provided with an opening, a cover for closing the opening, an outlet shut-off valve secured 60 to the cover and communicating with the interior of said casting, an inlet shut-off valve secured to the cover and communicating with the interior of the casting, a straining element disposed between the inlet shut-off valve 65 and the cover for straining a refrigerant

fluid, means for securing the inlet shut-off valve to the cover and for holding the straining element between said valve and the cover, and float-operated valve means carried by the cover and arranged for shutting off the 70 flow of the refrigerant liquid to the interior of the casting.

Signed at Chicago in the county of Cook and State of Illinois this 27th day of February A. D. 1929.

RAYMOND C. HAIMBAUGH.
ANTHONY F. HOESEL.
